[57] CLAIM

The ornamental design for a combined lounge chair, adjustable table and accessory shelf, and shown and described.

DESCRIPTION

FIG. 1 is a perspective view of my combined lounge chair, adjustable table and accessory shelf showing my design, the same being shown from side and the front thereof with the back inclined, foot rest extended and the table turned to a reading position, and

FIG. 2 is a perspective view of my combined lounge chair, adjustable table and accessory shelf showing my design as viewed from the opposite side and back with the back raised, the foot rest retracted and the table turned to an alternate position.
